(57) **CLAIM**

The ornamental design for a footwear outsole, as shown and described.

DESCRIPTION

FIG. 1 is a rear bottom perspective view of a footwear outsole, showing our new design;

FIG. 2 is a bottom view thereof;

FIG. 3 is a front perspective view thereof; and,

FIG. 4 is an enlarged view of FIG. 1 that omits the unclaimed subject matter.

The broken lines of uneven length adjacent the shaded area are boundary lines that form no part of the claimed design. The remaining broken lines of uneven length illustrating an example footwear form no part of the claimed design. The stippling on the figures represents shading and not surface ornamentation.
